UNITED STATES PATENT OFFICE.

WILLIAM H. HEINZ, OF DAYTON, OHIO.

FOUNTAIN-BRUSH.

SPECIFICATION forming part of Letters Patent No. 427,078, dated May 6, 1890.

Application filed March 1, 1889. Serial No. 301,724. (Model.)

To all whom it may concern:

Be it known that I, WILLIAM H. HEINZ, a citizen of the United States, residing at Dayton, in the county of Montgomery and State 5 of Ohio, have invented certain new and useful Improvements in Fountain-Brushes; and I do hereby declare that the following is a full, clear, and exact description of the invention, which will enable others skilled in the 10 art to which it appertains to make and use the same, reference being had to the accompanying drawings, and to the letters and figures of reference marked thereon, which form a part of this specification.

15 My invention relates to improvements in fountain-brushes, the same consisting of a reservoir, a scrubbing-brush, and a rubber cleaner united in one implement and having a suitable handle for operating the same. The 20 object of uniting these several parts is to do scrubbing and complete the cleaning by a single implement. I attain the object by the construction illustrated in the accompanying drawings, in which—

25 Figure 1 is a transverse section of the implement on line *x*, Fig. 3. Fig. 2 is an end view of the same, showing the plate of the handle partly in section. Fig. 3 is a front view of the same, this and the former view 30 not showing the brush material. Fig. 4 is a top view of the plate.

Like letters and numbers designate like parts throughout the several views.

A is a tin vessel having the length of the 35 brush-block to which it is attached, and in transverse section is generally circular and having an acute angle at the lower left corner, and from this angle a ribbed plate 7 extends horizontally through a slot in the brush-block B. Ears 8 are formed at both ends and screws entering through the same secure the fountain to the brush. An ordinary screw-cap of parts 5 and 6, the former being soldered to the bottom of the fountain, is used 40 for the purpose of filling the same. To the cap 6 is attached the air-tube 9, which serves to furnish air to the top of the fountain that the flow may be uninterrupted.

On one end of the fountain is soldered a 45 square loop of wire and on the other a hook of similar form. These parts engage the

square rod of steel 4, and thereby secure the wiper to the upper back portion of the fountain. In the detachable metallic trough 2 is placed the folded rubber 3, and on this is 55 placed the rod of steel and secured to the fountain, as specified.

The brush-block B is constructed in the usual manner, having orifices to receive the hair or other material, with the exception of 60 a central slot extending nearly the length of the said block. This slot is to accommodate the extension of the fountain used to carry the water onto the brush material at a point nearly central between the same. At the 65 bottom of the block is an extension to which the plate D is attached, and it is only necessary to make a secure fastening for said plate, which is secured by wood-screws to the block.

E is the handle, having a socket in its outer 70 end to receive a wooden handle. On its inner end are lateral cylindrical extensions that occupy the housing of the plate, and beneath is a lug to arrest the downward movement of the handle, and the upper is arrested by the 75 side of said housing. Beneath the pivot of the handle is placed a piece of rubber 10, to give rigidity to the movement of the handle. At Fig. 3 *m* is the orifices of the block, *n* orifices of the fountain, and 7 the ribbed distributor. The ribs serve to prevent the water flowing sidewise along the same.

The operation is thus: The reservoir or fountain is filled from the bottom through the screw-cap, the brush is then moved to and 85 fro over the surface of a window or floor, the water flowing out centrally within the brush material, and when the scrubbing is completed the wiper is used to complete the cleansing operation by making the surface comparatively dry.

Having fully described my invention, what I claim, and desire to secure by Letters Patent, is—

1. In a fountain scrubbing-brush, the combination of the vessel A, having the ribbed projection 7, and over the same a series of orifices *n* and ears 8, and the centrally-slotted block B, supplied with brush material, substantially as set forth. 95

2. In combination with a fountain scrubbing-brush, the wiper comprising the metal 100

channel 2, the rubber 3, and elastic bar 4, secured to the fountain by wire loops soldered to the ends to engage said bar, substantially as shown and described.

5 3. In a fountain scrubbing-brush, the combination of the closing screw-cap 5 6 in the bottom of said fountain, and the air-tube 9, attached to said closing part 6, to convey air to the top of the interior of said fountain, substantially as set forth.

4. The brush-handle comprising the pivotal plate D, socket-handle E, with cylindrical

head and arresting-lug beneath, and the rubber 10, in combination with the longitudinally-slotted brush-block B, substantially as described. 15

In testimony that I claim the foregoing as my own I affix my signature in presence of two witnesses.

WILLIAM H. HEINZ.
